STREAM FEEDER DEVICE

Harry W. Faebel, Larchmont, N. Y., assignor to Time, Incorporated, New York, N. Y., a corporation of New York

Application April 22, 1954, Serial No. 424,929

7 Claims. (Cl. 271—11)

This device relates to improvements in devices for feeding sheet material and it relates particularly to an improved form of mechanism for feeding signatures to gathering machines, inserters, stuffing machines, collating machines and the like.

Many devices have been provided heretofore for feeding signatures (printed sheets or groups of printed sheets folded to form a plurality of pages of a book, magazine or the like) to the various types of machines used for assembling the signatures into books, magazines, periodicals and the like. The prior machines have included grippers by means of which the signatures are withdrawn from the bottom or front of a stack with the assistance of suitable suction fingers and carried into a position to be dropped on a conveyor or other device in which the signatures are assembled. The prior devices are limited in their speed because of the reciprocating grippers which have to perform an empty return stroke to pick up the next signature, which introduces unproductive time into the cycle of operation.

The present invention involves an improved feeding mechanism by means of which a continuous stream of overlapping signatures can be fed to a receiving conveyor or the like while operating at relatively low speed. The new mechanism utilizes a plurality of grippers which perform the feeding function while rotating continuously, thus eliminating the idle return time.

For a better understanding of the present invention, reference may be had to the accompanying drawings in which:

Fig. 1 is a view partly in section and partly in elevation of the feeding mechanism of a feeding device embodying the present invention;

Fig. 2 is an exploded perspective view of one gripping member of the feeding mechanism disclosing details thereof and;

Figs. 3 to 10 are schematic illustrations of the procedural steps and operations involved in the feeding of the signatures from a stack thereof.

The invention will be described with reference to its use in conjunction with elements which are conventional in the art and have been used heretofore in connection with signature feeding mechanisms. For example, as shown in Figs. 3 to 10, inclusive, it is old to provide a chute or pocket 10 for receiving a stack of signatures, the pocket having an end flange 11 against which the folded ends of the signatures S¹, S², S³, etc. rest and inwardly projecting pins 12 along the bottom edge of the flange which support the folded edges of the signatures. The chute also has a bottom plate 13 which extends from its rear edge to a suction roll 14 that aids in withdrawing the signatures as explained hereinafter. Also cooperating with the mechanism described above are pairs of suction fingers 15 and 16 of partly conventional type. The suction finger 15, as shown in Fig. 3, is advanced beneath the bottom signature S¹ and suction is applied to the suction opening 17 therein for engaging the bottom signature S¹. The finger 15 then rocks to pull the folded edge of

2

the signature S¹ downwardly past the pins 12, as shown in Fig. 5. In the meantime, the suction finger 16 advances to hold the next signature S² against downward movement. In conjunction with the suction roller 14, the signature S¹ is directed downwardly by the novel curved undersurface 16a of the finger 16, as shown in Figs. 6 and 7, into the gripper member 20 on the feed roller 21, forming the novel structure of the present invention. It will be seen that the suction fingers 15 and 16 gyrate relative to the chute 10 and alternately pick off the lowermost signature and direct it downwardly to be engaged by a gripper member 20 for removal from the stack and delivery to the conveyor 22 or the like shown in Fig. 1. The mechanism described above, with the exception of the curved underside and alternate action of fingers 15 and 16, the feed roller 21 and the grippers 20 thereon, is conventional. The feed roller 21 may be one or more cylinders or disks 23 on each of which a plurality of the grippers 20 are mounted. As shown in Fig. 1, a typical feed roller 21 may include six grippers 20a, 20b, 20c, 20d, and 20e, all of which are essentially identical so that only one of them will be described herein. For example, the gripper 20 includes a pair of gripping jaws 25 and 26 which have elongated arms 27 and in-turned outer ends 28 for gripping the folded edge of a signature. Meshing gear segments 29 and 30 are formed on the grippers 25 and 26 at their inner ends so that they rock simultaneously toward and away from each other. The gripper arm 26 is mounted on the disk 23 by means of a screw threaded stud 31 which extends through a generally oval-shaped mounting block 32, and an opening 33 in the jaw 26 concentric with the gear 30 and is threaded in an internally threaded hole 34 in the disk 23. In this way, the arm 26 and the block 32 can rock relative to the screw 31 when it is tightened down.

An unthreaded pin 35 passes through a hole 36 in the jaw 25 concentric with the gear segment 29, through a hole 37 in the block 32 through an elongated hole 38 in a cam follower member 39 and the end of the pin 35 is received in the hub 40 of a lever 41. The jaw 25 and the lever 41 are secured non-rotatably to the pin 35 by means of suitable cross pins 42 and 43 so that they move together but can rotate relative to the mounting block 32 and the cam follower arm 39.

The cam follower arm 39 is provided with a hub 45 which rotatably receives the smooth shank 46 of a screwed stud 47 which is threaded into an opening 48 in the disk 23 so that the cam follower hub 45 is rotatable relative to the stud 47. The cam follower 39 has an elongated arm of arcuate shape containing the elongated opening 38 and carries at its outer end a rotatable follower roller 49 which is secured to it by means of a stud 50.

Another cam follower member 51 which has an opening 52 therein in alignment with the hub 45 is movably carried by the screw so that the two cam followers 39 and 51 can move relatively. The cam follower 51 also has a follower roller 53 mounted on a stud 54 and has a pin or shaft 55 extending beneath the lever arm 41.

The jaw 25 is biased in a clockwise direction and the jaw 26 in a counter-clockwise direction by means of a coiled spring 60 which is connected between a pin 61 on the back of the arm 25 and a pin 62 threaded in a hole 63 in the disk 23.

A spring 65 extending between a pin 66 on the underside of the arm and an anchor pin 67 fixed to the disk 23 biases the cam follower 39 in a counterclockwise direction. The cam follower 39 cooperates with a cam disk 70 coaxial with but spaced from the end of the disk 23 and the cam follower 51 cooperates with a similar coaxial cam disk 71. The cam disk 70 is provided throughout about 90° of its periphery with a raised

lobe 70a while the remainder 70b of the edge of the cam is essentially circular except for the rise and fall to and from the raised lobe.

A similar raised cam lobe 71a extends through about 60° of the arc of the cam 71.

The cams 70 and 71 are maintained stationary by supporting them on a fixed shaft 72 while the disk 23 is rotated to cause the grippers 20 to 20e to move through a circular path. The disk 23 may be rotated by a gear, pulley or sprocket (not shown) mounted on its back and driven in geared relationship to the fingers 15 and 16 to synchronize them.

Usually, two of the feed members 21 will be mounted in spaced relation on the shaft 72 to engage each signature at spaced points along its folded edges. As shown in Fig. 1, the gripper 20 is in such a position that the follower rollers 49 and 51 engage the crests or lobes 70a and 71a of the cams. In this position, the follower 51 is rocked clockwise so that the pin 55 thereon raises the lever 41 and rotates it counter-clockwise. Counter-clockwise rotation of the lever 41, in turn, rotates the jaw 25 counter-clockwise because they are connected together by the pin 35. Due to the geared relation of the jaws 25 and 26, the jaw 26 is rocked clockwise about its supporting pin 21 so that the jaws are open. When the gripper 20 advances to a position corresponding to the position of the gripper 20a, the cam follower roller 53 of arm 51 is off the lobe 71a thereby moving arm 51 in a counter-clockwise direction. Such movement of the cam follower 51 allows the spring 60 to move the lever 41 and the jaw 25 in a clockwise direction.

Inasmuch as the jaws 25 and 26 are connected by the gear segments 29 and 30, the jaws 25 and 26 close and engage the end of a signature S³, for example. Further movement of the disk 21 brings the gripper 20 to the position shown and corresponding to the position of the gripper member 20b. In this position, the follower roller 49 has moved off of the lobe 70a of the cam 70 and is in engagement with the low portion of the cam. Due to the action of the spring 65, the follower 39 has been rocked in a counter-clockwise direction and by engagement with the pin 35 has caused both of the gripper fingers 25 and 26 to pivot backwardly around the axis of the pin 31 thereby canting the entire gripper assembly rearwardly to prevent creasing and tearing of the signature S², for example.

Continued movement of the disk 21 brings the gripper finger 20 to the position corresponding to the gripper 20d. In this position, the cam follower roll 53 moves up onto the crest 75 of an adjustable segment 76 of the cam 71 a sufficient distance to rock the lever 41 slightly in a counter-clockwise direction and thereby move the finger 25 counter-clockwise and the finger 26 clockwise to open them and allow the signature to be diverted downward by guide 22a and drop onto the conveyor 22. The gripper fingers remain in this relation until they return to the position of the gripper 20, shown in Fig. 1 ready for another cycle of operations.

There will be seen from the description of the arrangement of the gripper fingers on the drum 21 and their cycle of operation that a plurality of such signatures are at all times engaged and held by the gripper fingers in overlapping relation so that a continuous stream of the signatures can be fed by the new feeding mechanism. Inasmuch as they are fed in overlapping relation, it will be apparent that the new feeding mechanism is capable of feeding them at much higher rates than the prior devices in which the signatures are fed in end-to-end relation, with substantial gaps in between. In this way, it is possible to feed the signatures faster without increasing the speed of the feed mechanism or the feed member 21 can be rotated slower than the feeders of the prior devices while feeding an equal number of signatures.

It will be understood that the device may be used with many different types of apparatuses to which signatures,

sheets or the like are fed for treatment therein. It will be understood also that the number of grippers 20, 20a, etc., may be varied as may be desired and that other changes in form, size and proportions may be made without departing from the invention. Therefore, the form of the invention described herein should be considered as illustrative and not as limiting the scope of the following claims.

I claim:

10. A device for feeding signatures and the like comprising means for successively freeing one edge of successive signatures in stack, a rotary member, a plurality of grippers spaced angularly around the periphery of said rotary member, each gripper including a pair of jaws movable relative to said rotary member and to each other to open and closed positions, means to rotate said rotary member, cam means for opening and closing said jaws in response to rotation of said rotary member to grip the freed edges of successive signatures and advance them in overlapping relation to a place of discharge, means supporting said grippers for rocking movement relative to said rotary member and cam means for moving said grippers between a substantially radial position on said rotary member and a rearwardly inclined position with relation to the direction of rotation of said rotary member to avoid tearing said signatures.
15. The device set forth in claim 1 in which the spacing between said gripping members is less than the length of said signatures thereby to advance the signatures in overlapping relation to the place of discharge.
20. 2. The device set forth in claim 1 in which the spacing between said gripping members is less than the length of said signatures thereby to advance the signatures in overlapping relation to the place of discharge.
25. 3. A device for feeding signatures and the like, comprising a rotary member, a plurality of grippers mounted in angularly spaced relation around the periphery of said rotary member, each gripper comprising a pair of jaws, pivot means fixed to said rotary member supporting one of said jaws for rocking movement, a supporting member pivotally mounted on said pivot means, means supporting the other jaw for rocking movement on said supporting member, gear means connecting said jaws for relative rocking movement into open and closed positions, a first cam member adjacent to said rotary member, first cam follower means pivotally mounted on said rotary member and engaging said first cam member, said first cam follower means being connected to one of said jaws and responsive to relative movement between said rotary member and said first cam member for opening and closing said jaws, a second cam member adjacent to said rotary member and a second cam follower member pivotally mounted on said rotary member and connected to said supporting member for rocking it and the jaws relative to said rotary member in response to relative movement between said rotary member and said second cam member.
30. 4. The device set forth in claim 3 in which said first and second cam members are fixed in position.
35. 5. The device set forth in claim 3 comprising spring means normally biasing said jaws to closed position and biasing said first cam follower member against said first cam member.
40. 6. A device for feeding signatures and the like comprising means for successively freeing one edge of successive signatures in stack, a rotary member, a plurality of grippers spaced angularly around the periphery of said rotary member, each gripper including a pair of jaws movable relative to said rotary member and to each other to open and closed positions, meshing gear segments on said jaws connecting them for relative movement, means to rotate said rotary member, cam means for opening and closing said jaws in response to rotation of said rotary member to grip the freed edges of successive signatures and advance them in overlapping relation to a place of discharge, cam follower means engaging said cam means and connected with said jaws for moving them, means supporting said grippers for bodily movement between a substantially radial position on said rotary mem-

ber and a rearwardly inclined position with relation to the direction of rotation of said rotary member, and a cam and cam follower member for rocking said grippers to said position.

7. A device for feeding signatures and the like comprising means for supporting a stack of signatures, means adjacent to said stack supporting means for freeing one edge of successive signatures from said supporting means, a rotary member, means supporting said rotary member for rotation with a portion of its periphery adjacent to said stack supporting means and to the free edges of said signatures and with the lowermost signature substantially tangent to said periphery portion, a plurality of gripping members angularly spaced around the periphery of said rotary member, said gripping members being spaced apart a distance less than the length of said signatures, each gripping member having jaws relatively movable between

open position and closed position, means for rotating said rotary member to move the gripping members toward said stack supporting means and substantially in opposition to the free edges of said signatures, and means responsive to rotation of said rotary member for opening and closing said jaws to grip the free edges of a plurality of said successive signatures while they are at least partially on said stack supporting means and withdraw them from said stack supporting means and advance them in overlapping relation to a place of discharge.
